BICYCLE

Jack Fried, 1451 S. Bedford St., Los Angeles, Calif.

Filed Jan. 21, 1965, Ser. No. 83,519

Term of patent 14 years

(Cl. D90—8)

FIG. 1.

FIG. 2.

The dominant features of my design reside in the portions shown in full lines.

I claim:

The ornamental design for a bicycle, as shown and described.
